UNITED STATES PATENT OFFICE.

LAWRENCE ABRAHAM, OF NEW YORK, N. Y.

PACKING-TABLE.

No. 888,681.

Specification of Letters Patent.

Patented May 26, 1908.

Application filed March 21, 1908. Serial No. 422,451.

To all whom it may concern:

Be it known that I, LAWRENCE ABRAHAM, a citizen of the United States, and a resident of the borough of Brooklyn, county of Kings, 5 city and State of New York, have invented certain new and useful Improvements in Packing-Tables.

My invention relates to packing tables such as are used in large department stores 10 and has for its object to so construct tables of this description that articles which have been sold are wrapped and passed to the delivery department in the order in which they have been purchased.

15 With my improvement packages which have been sold first are sent out with the early deliveries and are not at the bottom of the heap of later sales and thus sent out last as is at present the case.

20 My invention will be fully described hereinafter and the features of novelty will be pointed out in the appended claim.

Reference is to be had to the accompanying drawings in which Figure 1. is a front 25 view of my improved table and Fig. 2. is a sectional view thereof on a line 2—2 of Fig. 1.

In the drawings A represents the top board of the table which is secured to end standard B so as to leave a free space under said top 30 board A.

C and C' are standards secured to the top board A in any suitable manner near the back edge thereof and connected by a cross bar D to form a suspending frame. The

35 standard C has secured to its upper end a disk C' bearing the designation "on" and the standard C' has secured to it a similar disk, D², having the designation "off" thereon.

E. are bags made of canvas or other suitable material and provided with eyelets E' near the open end thereof. One end of hooks F is arranged to hook into these eyelets E' the other end of said hooks being adapted for engagement with the cross bar D.

45 G is a box or receptacle located in the space under the top bar A in which the bags E are placed when not in use. A rod H is carried by brackets H' which are secured to the receptacle G on which hooks F are hung when

50 said hooks are idle.

In using the device the articles which have been sold are carried to the person in charge of the wrapping desk, who places said article or articles in one of the bags E and then adjusts one of the hooks F in position on said

bag and hangs the same on the cross bar D near the pedestal C marked "on." As the next article is bought to the person in charge of the table, the operation is repeated and the second bag also hung on the rod D. to the 60 left of the first hook, or, in other words, between the first hook and bag and the pedestal C. Thus each succeeding article which is delivered to the table is placed in a bag, which bag is hung on the rod D to the left of the 65 next preceding bag, so that the line of bags with the articles therein is gradually moved to the right in Fig. 1. or, toward the pedestal marked "off" in the direction indicated by the arrow in Fig. 1. As the person in charge 70 has time, the bag nearest the pedestal C' is removed from the bar D and the contents thereof wrapped up for delivery, after which, the empty bag is placed in the receptacle G and the hook F is hung on the rod H for 75 future use. With my improved table the articles which have been sold are successively wrapped and are at all times handed to the delivery department in the order in which the sales have taken place. In the event of 80 a special delivery such article is marked in any suitable manner according to the system in use in the particular establishment and is placed in a bag which is then immediately hung on the bar at the head of the line of preceding bags. This special delivery sale is thus wrapped up as soon as it is received by the wrapper and immediately handed to the delivery department for delivery.

With my device the line of bags moves 90 continually toward the pedestal marked "off", thus always leaving room near the "on" side of the device for new purchases. By having the hooks movable from the bar D the necessity for placing new goods in 95 front of articles sold prior to such purchases, as would be the case if the hooks F were fixed to the bar D, is done away with. The hanging cloth bags keep individual sales absolutely free and separate from other sales 100 and do away with the necessity for the packer to carefully read the sales slip. The old method required a heaping up of sold goods, so that the top of the heap would receive first attention and the goods which 105 were sold first and which were at the bottom of the heap received last attention. Further it was necessary for the packer to read each sales slip very carefully and select his merchandise from the description on the slip, 110

this resulting very often in wrong deliveries. By keeping the unwrapped merchandise away from the packer's table and suspending same on a rod, the packer can handle only 5 one customer's purchases, that is the contents of a single bag at a time, thus preventing mix-ups which occur with the present methods. By having separate hooks for each bag, the bags and the hooks may be kept in a 10 separate receptacle so as to be continually available for use. By having the receptacle for containing the empty bags adjacent to the packer, the empty bags may be returned to the supply box at once, thus maintaining 15 a steady supply of bags. The suspension of merchandise in bags prior to being packed prevents delicate articles from being crushed, as is the case when the goods are piled in a heap. The bags also keep the merchandise 20 from the soil and dirt of the packer's table.

Various modifications may be made with-

out departing from the nature of my invention as defined in the claim.

I claim:

The combination of a packing table, a suspending frame secured to said table and extending upwardly therefrom, hooks arranged to move along said frame, bags adapted to contain articles of merchandise and to be suspended from said hooks so as to be consecutively removable, a receptacle secured to said table and adapted to contain the bags when not in use, and a bar extending lengthwise of the receptacle on which said hooks may be hung when idle. 25 30 35

In testimony whereof I have hereunto set my hand this 18th day of Mch. 1908.

LAWRENCE ABRAHAM.
